UNITED STATES PATENT OFFICE.

EARL E. EBY, OF WILKINSBURG, PENNSYLVANIA, ASSIGNOR TO WESTINGHOUSE ELECTRIC AND MANUFACTURING COMPANY, A CORPORATION OF PENNSYLVANIA.

AUTOMATIC PUMPING SYSTEM.

1,248,467.

Specification of Letters Patent. Patented Dec. 4, 1917.

Application filed November 29, 1915. Serial No. 64,046.

To all whom it may concern:

Be it known that I, EARL E. EBY, a citizen of the United States, and a resident of Wilkinsburg, in the county of Allegheny, 5 and State of Pennsylvania, have invented a new and useful Improvement in Automatic Pumping Systems, of which the following is a specification.

My invention relates to automatic pumping systems, and it has for its object to provide means whereby pumping apparatus may be automatically connected to, and disconnected from, the interior of a closed container, in accordance with pressure changes 10 therein, in a simple and effective manner.

The single figure of the accompanying drawing is a diagrammatic view of the various elements of a pumping system embodying my invention.

20 In the operation of various types of exhausted apparatus, such, for example, as vapor converters of the metal-case type, it is desirable that the vacuum be maintained at a certain value, and, if minute leaks are 25 present, it is necessary that pumping apparatus be connected thereto from time to time. It is furthermore desirable to employ a valve of the solid-seal type, such as is disclosed and claimed in a copending application 30 of E. E. Rose, Serial No. 61,085, filed Nov. 12, 1915, and assigned to the Westinghouse Electric & Manufacturing Company, between the exhausted container and the pumping apparatus. It is still further desirable, with the extremely high degree of 35 vacuum employed in apparatus of the character specified, that the pumping apparatus itself be highly exhausted when connection is made to the container.

40 By my invention, I provide means whereby, when the degree of vacuum within the container falls to a predetermined value, a pumping device is first actuated to exhaust itself to a high value, a valve is then opened 45 to connect said exhausting device to the container and, furthermore, whereby, when the vacuum within the container has been raised to a predetermined value, said valve is first closed and said pumping device is there- 50 after stopped.

Referring to the accompanying drawing for a more detailed understanding of my invention, a vapor converter of the metal-case type is shown at 1 and embodies a main 55 anode 2, a main cathode 3 and a keep-alive

circuit 4, as is usual in the art. A vacuum gage 5 of the hot-wire type is exposed to the interior of the container 1 and is connected to a bridge 6 for the operation of a relay 7, all as is shown and claimed in a copending application of William Tschudy, Serial No. 50,077, filed Sept. 10, 1915, and assigned to the Westinghouse Electric & Manufacturing Company. Briefly, the device 5 embodies a relatively high-resistance filament through 65 which current is continually caused to flow. Variations in the pressure of the gas surrounding said filament affect the heat radiation therefrom so as to cause radical changes in the resistance thereof, whereby the balance of the bridge 6 is disturbed to bring about the operation of the relay 7 in a similar manner to the operation of the galvanometer in the ordinary Wheatstone bridge. 75

Pumping apparatus comprising a "roughing" pump 8 and a "finishing" pump 9, driven by a suitable motor 10, is connected to the interior of the container 1 through the valve 11 of the solid-seal type, as described and claimed in the above-mentioned application of E. E. Rose. Briefly speaking, the valve 11 comprises an upwardly extending tube 12 surrounded, at its upper end, by an annular pool 13 of readily fusible material, such, for example, as solder. A cap 14 surmounts the upper edge of the tube 12 and, when the lower edge is submerged in the pool 13, causes a tight and effective closure of the said tube 12. A solenoid 15 surrounds the valve and is arranged to actuate an armature 16 to raise and lower the cap 14, as desired. A heating winding 17 surrounds the valve 11 adjacent to the pool 13 for the fusion thereof. A thermostatic circuit closer 18 is intimately associated with the winding 17 for a purpose to be herein-after pointed out. 85 90 95

A wire-type vacuum gage 19, similar to the gage 5, is mounted so as to be exposed to the interior of the "finishing" pump 9 and controls the operation of a bridge 20 which, in turn, operates a relay 21. A double-coil electro-magnetic switch 22 is arranged to be operated by the relay 7 and to supply current to the motor 10 from a suitable source 23 and, in like manner, an electromagnetic switch 24 is arranged to be controlled by the relay 21 and to supply current to the solenoid 15 and to the heating winding 17. 100 105 110

Having thus described the structure of a pumping system embodying my invention, the operation is as follows: Assuming a high, but gradually falling, degree of vacuum within the container 1, the resistance of the filament within the gage 5 gradually changes until the bridge 6 is unbalanced to such a degree as to cause the upward movement of the contact member of the relay 7, 10 energizing the closing coil of the electromagnetic switch 22 and supplying current to the motor 10 through wires 25 and 26, thus starting the pumps 8 and 9 into operation. When the vacuum within the pump 9 is 15 raised to a value equal to, or higher than, that in the container 1, the gage 19 causes such unbalancing of the bridge 20 as to operate the relay 21, energizing the electromagnetic switch 24 and closing a circuit to 20 the solenoid 15 and to the heating winding 17 through wires 27 and 28. Fusion of the pool 13 and the raising of the cap 14 by the armature 16 follows, and the pumping apparatus is operatively connected to the interior of the container 1.

When the vacuum within the container 1 has been raised to a predetermined high value, the resistance of the gage 5 so alters as to unbalance the bridge 6 in the reverse 30 manner from the former case, causing the contact member of the relay 7 to move downwardly, closing a circuit to the opening coil of the electromagnetic switch 22. The connection of the wire 25 to the source 23 is, 35 therefore, broken, the solenoid 15 and the heating coil 17 are deenergized and the motor 10 would stop were it not for the action of the thermostat 18. The deenergization of the solenoid 15 permits the armature 16 and 40 the cap 14 to drop, thus sealing the lower edge of the cap 15 in the fused sealing material 13. Were the pumps 8 and 9 stopped immediately, it might well happen that backward leakage therethrough would cause 45 sufficient accumulation of pressure above the cap 14 to force the fused sealing fluid into the container 1, with subsequent leakage. It is desirable, therefore, that the pumps 8 and 9 be operated for an appreciable period 50 of time, thus permitting the mass 13 to solidify and thereby acquire sufficient rigidity to prevent the above described action. To this end, the thermostatic circuit closer 55 18 is intimately associated with the heating coil 17 and placed in shunt to the contact members of the switch 22. When the heat coil 17 is energized, the device 18 is closed by the heat thereof and, accordingly, after the opening of the switch 22 and the consequent deenergization of the winding 17, 60 current continues to flow to the motor 10 through the device 18 for a considerable period of time, after which, solidification of the pool 13 having ensued, the motor 10 may 65 be permitted to stop.

While I have particularly described my invention in connection with the evacuation of a vapor converter, it will be obvious to those skilled in the art that it is capable of general application, not only in the control of the pressure within various types of evacuated apparatus but also for the accurate control of the pressure within containers adapted to operate at, or above, atmospheric pressure.

While I have described my invention in its preferred form, it will, furthermore, be obvious to those skilled in the art that it is susceptible of various other minor changes and modifications without departing from the spirit thereof, and I desire, therefore, that only such limitations shall be placed thereupon as are imposed by the prior art or are specifically set forth in the appended claims.

I claim as my invention:

1. The combination with a closed container, of exhausting apparatus associated therewith, a valve therebetween, and means for automatically starting said exhausting apparatus when the vacuum falls below a certain value and for subsequently opening said valve.

2. The combination with a closed container, of exhausting apparatus associated therewith, a valve therebetween, and means for automatically closing said valve when the vacuum in said container attains a predetermined value and for subsequently stopping said exhausting apparatus.

3. The combination with a closed container, of exhausting apparatus associated therewith, a valve therebetween, means for automatically starting said exhausting apparatus when the vacuum within said container falls to a certain value, and means for opening said valve when the vacuum within said exhausting apparatus has risen to a value equal to or higher than that in said container.

4. The combination with a closed container, of main circuit-controlling means associated therewith and operable in accordance with the degree of vacuum therein, an electrically controlled exhausting device connected with the interior of said container, and a circuit connecting said controlling means with said exhausting device whereby said device is started when the vacuum within said container falls below a predetermined value.

5. The combination with a closed container, of main circuit-controlling means associated therewith and operable in accordance with the degree of vacuum therein, an electrically controlled exhausting device connected with the interior of said container, an electrically controlled valve in the line between said exhausting device and said container, supplemental circuit-controlling

- means operable by the degree of vacuum within said exhausting device, and a control circuit connecting said devices wherein said exhausting device is directly subject to said 35
 5 main controlling means and whereby said valve is subject both to said main and to said auxiliary controlling means, whereby, upon a decrease in pressure within said container, said exhausting means are first operated until a pressure is attained therein substantially equal to that in said container and whereby said valve is then opened to connect the interior of said container to said exhausting device. 40
 10
 15 6. The combination with a closed container, of main circuit controlling means associated therewith and operable in accordance with the degree of vacuum therein, an electrically controlled exhausting device connected with the interior of said container, and a time element device associated with said exhausting device and arranged to maintain the same in operation for a definite period after the change in pressure 45
 20 within said container has caused the opening of the supply circuit by said main controlling device. 50
 25
 30 7. The combination with a closed container, of main circuit-controlling means associated therewith and operable in accordance with the degree of vacuum therein, an electrically controlled exhausting device connected with the interior of said container, a slow-acting electrically controlled 55
